H. M. SMITH,
BUFFING WHEEL,
APPLICATION FILED APR. 23, 1920.

1,413,942.

Patented Apr. 25, 1922.

UNITED STATES PATENT OFFICE.

HERBERT M. SMITH, OF FARMINGTON, CONNECTICUT, ASSIGNOR TO LANDERS, FRARY & CLARK, OF NEW BRITAIN, CONNECTICUT, A CORPORATION OF CONNECTICUT.

BUFFING WHEEL.

1,413,942.

Specification of Letters Patent. Patented Apr. 25, 1922.

Application filed April 23, 1920. Serial No. 375,931.

To all whom it may concern:

Be it known that I, HERBERT M. SMITH, a citizen of the United States, residing at Farmington, county of Hartford, State of Connecticut, have invented a certain new and useful Improvement in Buffing Wheels, of which the following is a full, clear, and exact description.

My invention relates to buffing wheels and has for its object to provide a paper buffing wheel in which the buffing surface is soft and fibrous. It further has for its object to produce an inexpensive wheel which will take the place of the cloth wheels now in use and largely, if not entirely, eliminate the use of cloth in buffing wheels for certain purposes.

The following is a description of a wheel embodying my invention, reference being had to the accompanying drawings, in which,

Fig. 1 shows a section of a wheel embodying my invention, through its center;

Fig. 2 is a side elevation of the same, parts being broken away; and,

Fig. 3 is an enlarged section through the center.

Referring more particularly to the drawings, 1 are four sections of the wheel, each of which comprises disks of embossed, crinkled, stippled, or otherwise corrugated paper of soft texture and having elasticity and flexibility in several directions. The crinkled wood pulp paper known as kraft paper, such as is used for crinkled paper towels or crinkled wrapping paper, is well adapted for my purpose. This paper is about 1/100th of an inch thick. It easily absorbs moisture. It is soft and pliable and wheels made up of it when used as buffing wheels present a soft matted edge, admirably adapted to receive and retain the materials used in buffing and other polishing operations. The disks of each section are stitched together with stitches 2. One suitable form of crinkled paper is indicated

in the drawings. Preferably the axes of the crinkles in the adjacent sheets are at an angle, as shown at 3-3' to produce uniformity and strength. I preferably face 50 the outer sides of the outer sections of the wheel with cloth as shown at 4 and 5 so as to protect the paper from tearing. Both sides of each section may be faced with cloth, in which case the body of the wheel 55 will have other layers of cloth as shown at 4'-5'.

The wheel may be made of any desired thickness and is preferably made up of a plurality of sections clamped on an ordinary 60 bushing 6 by a nut 7, the nut and bushing being provided with spanner holes 8. A wheel made up of paper such as described attains the objects of my invention and may be used in place of a cloth wheel with 65 very satisfactory results for many purposes.

As will be evident to those skilled in the art, my invention permits of various modifications without departing from the spirit thereof or the scope of the appended claims. 70

What I claim is:

1. A buffing wheel comprising contacting disks of soft corrugated paper forming a thick mass.

2. A buffing wheel comprising contacting 75 disks of soft corrugated paper having longitudinally extending crinkles, some of the layers of paper being placed so that adjacent layers have the crinkles angularly displaced.

3. A buffing wheel comprising contacting disks of soft corrugated paper forming a thick mass, said wheel having its outer faces composed of cloth.

4. A buffing wheel comprising contact- 85 ing disks of soft corrugated paper forming a thick mass, said wheel having its outer faces composed of cloth and having layers of cloth interposed between some of the sheets forming the thick mass.

HERBERT M. SMITH,
